UNITED STATES PATENT OFFICE.

BENJAMIN H. VAN AUKEN, OF SYRACUSE, NEW YORK.

WATER-FRONT FOR FIRE-POTS OF FURNACES.

1,076,082.

Specification of Letters Patent.

Patented Oct. 21, 1913.

Application filed July 3, 1912. Serial No. 707,539.

To all whom it may concern:

Be it known that I, BENJAMIN H. VAN AUKEN, a citizen of the United States, residing at Syracuse, in the county of Onondaga and State of New York, have invented certain new and useful Improvements in Water-Fronts for Fire-Pots of Furnaces; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in water heaters for hot air furnaces and the object in view is to produce a fire pot having an offset or recess formed 20 in the wall thereof for the reception of a water-containing tank and having communication with circulating pipes, the walls of the tank being preferably corrugated to allow for expansion and contraction of the 25 metal thereof.

The invention comprises various other details of construction and arrangements of parts which will be hereinafter fully described, shown in the accompanying drawings and then specifically defined in the appended claim.

My invention is illustrated in the accompanying drawings, in which:—

Figure 1 is a side elevation of a portion 35 of a fire pot, a portion of the same and the tank and recess containing the latter being shown in vertical section. Fig. 2 is a top plan view of the fire pot and tank, and Fig. 3 is a detail in elevation of the tank 40 showing inlet and exit openings therefor.

Reference now being had to the details of the drawings by letter, A and A' designate two sections of a fire pot, one superimposed upon the other in the manner shown, and 45 adapted to be cemented together. Said section A' is provided with an offset B, forming a recess or pocket, the opposite walls of which are grooved as at D, and E is a water

tank having its opposite edges E' corrugated to allow for expansion and contraction of 50 the metal of which it is composed, said tank being made preferably of a shape to conform to the curvature of the recess in the fire pot, and at each end of the tank is an integral flange F which is adapted to engage 55 said grooves to hold the tank securely in place. An inlet pipe H is connected to the tank E, preferably near its bottom, and at one end thereof, and through which pipe water is adapted to pass to the tank. An 60 exit opening N leads from the tank near its top and through which the heated water may pass and be piped, if desired, to any suitable location.

By the provision of a device as shown 65 and described, it will be noted that a simple and efficient hot water circulating system is afforded for ready attachment to ordinary hot air furnaces, utilizing the direct heat from the fire pot and affording additional heating system coöperating with the heat of radiation from the hot air furnace. In the event of it being desired to replace the tank, it may be done by simply disconnecting the pipes which pass through the 75 wall of the fire pot and, by removing the top off the fire pot, the tank may be released from its offset.

What I claim to be new is:—

In combination with the fire pot of a 80 furnace having a recess formed in the wall thereof, the opposite walls of the recess having vertical grooves, a receptacle conforming to and adapted to fit within said recess and having ribs at the ends thereof engaging the grooves in the end walls of the recess, the inner surface only of the receptacle being directly exposed to the heat within the fire pot, as set forth.

In testimony whereof I hereunto affix my 90 signature in the presence of two witnesses.

BENJAMIN H. VAN AUKEN.
